LUBRICANT RESERVOIR AND PUMP FOR
CENTRAL LUBRICATION SYSTEMSFrederick H. Gleason, Auburn, N. Y., assignor to
Bowen Products Corporation, Auburn, N. Y., a
Corporation of New York

Application June 18, 1928. Serial No. 286,310

16 Claims. (Cl. 184—28)

This invention relates to a certain new and improved lubricant reservoir and pump for central lubrication system.

This invention is adapted for use with lubricant distribution systems such as are disclosed in Gleason No. 1,580,823, April 13, 1926; Gleason No. 1,629,453, May 17, 1927; Gleason No. 1,592,199, July 13, 1926; Gleason No. 1,553,768, July 21, 1925; Gleason application Ser. No. 630,228, filed April 6, 1923; Gleason application Ser. No. 138,234, filed September 28, 1926; Gleason application Ser. No. 138,235, filed September 28, 1926; Gleason application Ser. No. 150,245, filed November 23, 1926; or with a system using improved capillary flow control resistances disclosed in a companion application about to be filed.

The main object of the invention is the production of a new and novel pump assembly contained within an oil reservoir whereby a highly efficient, comparatively inexpensive and easily manufactured source of oil supply under pressure adapted for use with central lubrication systems for lubricating machinery, automobiles and similar devices, is produced.

Other objects and advantages relate to the details of the structure and the form and relation of the parts thereof all as will more fully appear from the following description taken in connection with the accompanying drawings in which:

Figure 1 is an elevation of an apparatus of this invention installed upon an automobile.

Figure 2 is a section on line 2—2, Figure 1.

Figure 3 is a section on line 3—3, Figure 1.

Figure 4 is a section of a slightly modified form of device.

Figure 5 is a section of a further modified form of device.

Figure 6 is a section of another modification.

Figure 7 is a section on line 7—7, Figure 6.

Figure 8 is a section of a further modification.

Figure 9 is a top plan of perhaps a preferred embodiment of the invention.

Figure 10 is a section on line 10—10, Figure 9.

Figure 11 is a section on line 11—11, Figure 10.

The apparatus as shown in Figures 1 to 3 comprises an oil reservoir —1— consisting of a drawn steel shell —2— provided with a drawn steel cover —3— adapted to have a press fit on the reservoir shell —2—. The cover —3— is provided with an oil filler opening into which a closure —4— may be threaded. The cover —3—

is further provided with a substantially central opening surrounded by a threaded boss —5—. A pump cylinder guide and outlet assembly is provided at the bottom of the reservoir and this assembly includes a tubular fitting —6— provided with an external shoulder separated from the inner surface of shell —2— as by a gasket —7—. The fitting penetrates the wall of the shell —2— at its central portion and is locked in position by a nut —8—. A removable plug —9— is screwed into the bottom of the tubular fitting —6— with a suitable gasket —10— to provide an oil tight connection. The outlet tube —11— may be secured to plug —9— in any suitable manner as by tubing sleeve —12— and tubing nut —13—. The removable plug —9— supports a filter —14— which rests upon the raised edge of the plug and is spaced from the surface of the plug at the central portion of the latter. This filter may be held in position by spring —15— and the filter may be formed of a thin disc or capillary material such as aluminum or coarse porcelain or it may be one or more thicknesses of a very fine gauze meshed screen. A drawn shell or tube —16— has its lower end threaded into the boss —5— and is shouldered at —17— for a purpose to be hereafter described. A recess preferably of annular form is provided in the upper face of the fitting —6— for the reception of an annular gasket —18— of soft material such as leather or Vellumoid packing and the fitting is slotted at —19— just above the upper surface of gasket —18— to provide an oil port or passage from the reservoir to the cylinder —20—. When the latter is in raised position as shown in Figure 8 the fitting —6— has a portion extending upwardly into the reservoir above the gasket —18— and this portion is preferably of circular form and constitutes a ring or loose fitting guide —21— surrounding the lower end of the cylinder —20—. The upper end of cylinder —20— fits loosely within the lower enlarged end of shell —16— and the cylinder is of somewhat less length as for instance $\frac{1}{16}$ of an inch than the distance between the upper surface of gasket —18— and the inner surface of the shoulder —17— so that the cylinder is free to move up and down within the limits described. The pump cylinder —20— comprises a tube or cylinder having its lower end bent inwardly to provide an annular flange —22— which flange acts as a valve face in its contact against the soft gasket —18—. A piston —23— is arranged within the cylinder —20— and this piston, as illustrated, comprises a

leather cup washer 24 mounted upon the reduced end of piston rod 25 and held in place between washer 26 and headed nut 27 threaded upon the piston rod. The head of the 5 nut 27 is of sufficient size so as to contact with the inner surface of flange 22. The piston rod 25 extends upwardly through cylinder 20 and shell 16 and projects above the shell for securement to a suitable actuating 10 means as a flat flexible steel ribbon 28 which may be secured in the slotted end of the piston rod 25. Spring 29 is confined between washer 26 of the piston assembly and the end of the shell 16 and acts to normally hold 15 the piston assembly in the position shown in Figure 3.

As before suggested the cylinder 20 is a sloppy fit in its guide at both the top and the bottom and is free to line itself up regardless 20 of any spring or distortion in the reservoir shell or cover of the device.

The tube 20 may be designed for up and down movement within any desired limits as effected by frictional engagement of the moving 25 piston assembly with the interior surface of the cylinder as suggested a movement of $\frac{1}{16}$ of an inch is found satisfactory.

The downward movement of the cylinder is limited by contact of flange 22 with the 30 upper surface of gasket 18 and in that position the cylinder acts as a valve closing communication between the lower end of the cylinder and the reservoir.

When the piston assembly is drawn upwardly 35 carrying cylinder 20 along with it to a position as illustrated in Figure 8 oil is drawn from the reservoir into the cylinder, the upward movement of the cylinder being limited by shoulder 17 and when the piston has been 40 raised a sufficient distance to draw the required amount of oil, the spring 29 having been compressed by such movement, the spring thereafter acts to move the piston downwardly and in so doing moves cylinder 20 downwardly 45 until flange 22 strikes gasket 18 whereupon further movement of the piston will eject oil from cylinder 20 through fitting 6 into outlet tube 11.

The cylinder 20 may as shown be provided 50 with an opening 99 near its upper end permitting any lubricant in cylinder tube 20 above the piston assembly to return to the reservoir 1.

The annular hole in the top of drawn shell 55 16 through which piston rod 25 operates is positioned at a height above the maximum oil level of the reservoir 1 so that the portion of the piston rod 25 which comes out of this hole will not carry any oil out of 60 this hole. The slot 99 in the cylinder tube 20 allows any oil in cylinder tube 20 above the piston assembly to be returned to the reservoir 1 when the piston assembly is raised.

The combined tank and pump of Figure 3 can 65 be mounted in any suitable manner and as illustrated in Figure 1 is shown as secured to the frame 31 of an automobile. The lever 32 for actuating the piston may be pivoted upon the dash board 33 and extend through the dash board for manual operation from the driver's seat.

The flexible steel ribbon 28 may extend 70 around the cam head 34 upon the lever, however this structure is merely illustrative of

a suitable assemblage and method of operation.

The structure shown in Figure 4 is similar to the disclosure of Figure 1 except that the outlet fitting assembly includes a spring closed ball check valve 35 which normally prevents the 80 outflow of oil through the fitting except under pressure applied by actuation of the piston assembly. This check valve may be associated with any one of the structures herein disclosed in the manner illustrated in Figure 4.

Further a sleeve 36 is threaded upon the upper end of the drawn shell 16 and lock nut 37 is provided for maintaining the parts in any relative position of adjustment.

A cotter pin 38 is passed through the piston rod 25 so as to strike against the upper end of the shell 16 and against the inner wall of the sleeve 36 to limit the stroke of the piston. By this construction the stroke of the piston is made adjustable so that the pump may be set to deliver a certain volume of oil less than that delivered at full stroke. This construction is of use when the system is assembled to provide a continuous feed to a machine which is operated, as for instance, for 8 hours, 100 the controls of the distribution system being adjusted for a feed and the pump stroke adjusted so that the plunger will descend in approximately the same time interval that the machine is operated thus providing a continuous feed for the machine during operation.

A further modified form of structure is illustrated in Figure 5 in which the pumping device is adapted for operation by hydraulic or air pressure from any available source. In this 110 particular disclosure a drawn steel shell 39 is secured at its upper end by a tubular rivet 40 to the cover 3 of the tank and pressure conveying tube 41 is connected to the rivet 40 as by means of tubing sleeve 42 and tubing nut 43.

The line leading to the tube 41 may contain a three-way valve 44 which permits the supply of fluid under pressure to pipe 41 in one position of the valve and in another position 120 permits venting of the pipe 41 to the atmosphere as through outlet pipe 45. The shell 39 may perhaps preferably be of cylindrical form and depends within the oil reservoir and its lower end, as illustrated, is externally threaded for receiving the internal flange of a cap member 46 having a central opening surrounded by a boss 47.

The boss 47 acts as a guide for the piston cylinder 48 and the cap 46 acts as a stop to limit the upward movement of the cylinder 48. Cap 46 may be provided with a hole or opening 49 to permit the flow of oil into and out of the tube 39.

A leather cup washer 50 is assembled upon the upper end of piston rod 51 in any suitable manner as by being confined between washer 52 and nut 53 threaded upon the end of the piston rod 51, and spring 54 is interposed between the washer 52 and the cap 46 to normally maintain the piston assembly including cup leather 50 in its upmost position.

The oil pump piston is positioned in the cylinder 48 and although it may consist of a cup leather assembly it is illustrated as a metal piston 55 having a close fit within the cylinder 48. This form of piston is adapted for use with distribution systems employing controlled or metering devices such as are shown

in Gleason Patent 1,553,768, Gleason applications, Serial Nos. 630,228 and 150,245 in which it is necessary to relieve the pressure from the line to either permit the measuring device or controls to operate or to reload.

The use of this type of piston permits a very slow leak of oil by the piston until the piston reaches the end of its stroke when the oil pressure on the line will be relieved by the clearance 10 between the piston and the cylinder in which it moves.

When the metal piston such as —55— threaded or otherwise secured to the piston rod —51— is utilized, an expanding washer or friction 15 washer —56— is employed to provide the necessary friction to raise and lower the cylinder —48— in accordance with the movements of the piston. As shown, washer —56— is secured to the piston rod —51— and has a skirt portion 20 which is adapted to contact with the interior surface of cylinder —48—. The outlet fitting assembly is the same as that disclosed in Figure 1 and the lower end of the tube —48— is loosely guided in the same manner as the lower 25 end of the tube —20— and acts in the same manner in connection with the soft gasket —18—.

Figure 6 illustrates a further modified form of structure adapted especially to supply oil to 30 measuring devices which require a venting or release of pressure in the line to allow the control or measuring devices to reload. The structure, Figure 6, differs from Figure 5 in that the cap —46— is flanged outwardly so that its edge 35 contacts with the inner surface of the wall of the shell —2—.

In this manner the upper portion of the oil reservoir is separated from the lower portion except for a plurality of openings or passageways —57— through the flange or partition —58—, such openings being covered or closed by screens —59— or other filtering means.

The guide —60— for the cylinder —48— is considerably elongated and is formed integrally 45 with the fitting —6— so that the lower end of the cylinder —48— will always be guided to a correct seat on the soft gasket —18—.

In the disclosure, Figure 6, the guide flange or boss —47— is omitted and instead of metallic 50 piston —55— a cup leather assembly —24— is utilized similar to the piston assembly of Figure 1 except that the lower end of the piston rod —51— is formed with an axial conduit leading upwardly to a diametrically disposed conduit opening 55 into the cylinder —39—.

Any lack of alignment between the upper cylinder —39— and the lower cylinder —48— will be compensated for by a slight bending in the cup leathers of the upper and lower piston 60 assemblies.

The spring —54— in Figure 6 is held by a washer —62— that is free to locate itself upon the upper surface of the cap —46—.

For the purpose of providing a slow venting 65 or release of pressure in the system a pin —63— is positioned in the axial passageway in the lower end of the piston rod and piston and this pin nearly fills the passageway and is held in position in any suitable manner as by a cotter pin —64— positioned in the diametrical opening —65—. This structure provides a means to slowly allow oil to pass from cylinder —48— under pressure back into the cylinder —39— and the reservoir, in that manner relieving 70 any pressure that may be in the outlet tube

—12— and allowing the measuring devices to reload.

Figure 8 illustrates the same means for relieving pressure in the outlet tube by assembling in connection with a structure such as that shown in Figure 1. The operation, however, of the relieving means is exactly the same in Figure 8 as it is in Figure 6.

In Figures 8, 9 and 10 there is illustrated a perhaps preferred form of the invention. The structure there shown consists of a reservoir —70— including a cover —71— equipped with a removable oil screen —72— and a removable filler cap —73—. Further, the cover —71— is provided with an inverted cup shaped flanged shell —74— having an opening through which the piston rod —75— moves, this shell is held against the cover —71— by the action of the spring —76—, a gasket between the lower outwardly flanged diameter of the shell —74— and the bottom surface of the cover —71— providing an oil tight connection. Further this inverted cup shaped shell —74— constitutes an enclosure and stop for the upper end of spring —76— which actuates the piston in one direction and it also acts as a guide and stop for the upper 85 end of the cylinder —77— within which the piston moves, and as shown the upper end of the cylinder tube —77— is flared outwardly so that its free edge is loosely guided by contact with the interior surface of the member —74—. The outwardly flared upper end of cylinder —77— provides for the easy assembly of cup leather —87— in cylinder —77—. The opening in the top of the cup shaped flanged shell —74— through 90 which the piston rod —75— operates is positioned at a height above the highest oil level in the reservoir so that the portion of the piston rod —75— which comes in contact with the oil in operation of the piston rod —75— does not pass 95 through the opening in the top of the shell —74— through which the piston rod —75— operates preventing the rod from carrying any oil 100 out at this point.

The reservoir —70— is supported by a bracket —78—, having wings —79— which may be spot welded to the cover —71—, and by a bracket —100— which may be spot welded to the lower part of the reservoir shell —70—. These brackets may be secured to the dash of an automobile 105 or other place of attachment, as by bolts —80—.

The operating lever —81— may be made from pressed steel and hardened, the lever —81— is pivoted upon a pin or shaft —82— mounted in the opposed walls of the bracket —78— and is formed with two spaced cams or curved arms —83— disposed upon opposite sides of the piston rod —75— and positioned beneath the hardened enlarged head —84— upon the piston rod —75— so that the rocking movement of the operating lever —81— will elevate the piston within the cylinder —77— against the action of spring —76—.

Further, in order to maintain the operating lever —81— in the position shown in Fig. 10 110 ready for downward rocking movement by the foot or hand of an operator, torsion spring —85— is coiled about shaft —82— and has one arm or end in contact with the lever —81— and its other arm or end in contact with a stop member —86— which may be spot welded to the bracket —78— as best illustrated in Fig. 10 so that downward movement of lever —81— tensions this spring and the spring will return 115 the lever to the position shown in Figure 10 120

after each operation of the lever —81—. The spring —85— prevents any noise or rattle that might be due to play in the assembly of lever —81— on pin —82— in bracket —78—, and it 5 also prevents any stiffness or binding of lever —81— from detracting from the effective push of the piston spring —76—. Lever —81— is always maintained up in position shown in Fig. 10 so that it is always out of the way of the 10 feet of the vehicle operator except when lever —81— is being depressed. Stop member —86— also nearly closes the U shaped section of the lever —81— practically preventing any air circulation through the opening in the dash 15 through which the lever —81— passes.

The piston rod —75— is provided at its lower end with a piston assembly comprising a flat washer —105—, a cup leather piston —87—, a cup leather metal expander —104—, and a nut 20 —88—, all of the parts being clamped against the shoulder on the lower end of the piston rod —75— by the nut —88— threaded on the reduced diameter of piston rod —75—. The nut —88— is adapted in the lowermost position of 25 the piston rod —75— to seat upon the inturned flange —89— of the cylinder tube —77— and this flange in turn seats upon the resilient washer —90— which constitutes a valve seat 30 to prevent communication between the reservoir —70— and cylinder tube —77— through openings or passageways —91— formed in the upstanding circular guide flange —92— formed in the tubular outlet fitting —93— which may, as shown, be threaded into the reservoir —70—. 35 Suitable packing —94— is preferably interposed to form an oil tight joint.

The lower end of the piston rod —75— is 40 formed with an axial passage or hole —95— drilled therein and extending upwardly a desired distance, and this passage communicates with the interior of the cylinder tube —77— above the piston assembly on piston rod —75— through two radial passages —96— and —97—, passage —96— being formed near the upper end 45 of passage —95— while passage —97— is formed part way down the passage —95— and at an intermediate point along the latter. An oil relief pin —98— is positioned in the passage —95— and is of slightly less diameter than the interior 50 diameter of the passage —95— so as to permit the flow of oil through passage —95— around the pin —98— to the radial passageways —96— and —97—, and at an intermediate point along the pin —98— there is provided a reduced portion 55 which may lie opposite the passage —97— for a purpose to be described.

A leak pin of the kind here illustrated is quite 60 sensitive to dirt or strands of lint that may be contained in the lubricant, and in order to make the pin self-cleaning at each operation of the pump, the pin is loosely held in the outlet fitting —93— by means of a short round pin —99— passed through the lower end of the relief pin, and the outlet fitting —93— through which 65 the relief pin extends is of sufficient size so that there is always an oil passage by the relief pin permitting flow of oil through the outlet fitting past the relief pin, and the relief pin is loosely held between the shoulder in the oil passage in fitting —93— and the top of the tubing connection fitting —101—, the tubing fitting —101— being assembled in an oil tight manner by means of a gasket —102— and threaded portion, the relief pin may be installed and removed 70 by removing the tubing connection —101—, the

construction providing for the relief pin being loosely held so that it can fit the oil passage —95— without binding. The difference in diameters between the passageway —95— and relief pin —98— is such as to provide the desired rate of oil leak and at each operation of the piston rod —75— the piston in moving up and down passes over the exterior surface of the relief pin —98— and breaks up any dirt that may be forced into the clearance between the pin and the passageway —95—.

This dirt will be scraped off at the point where the pin enters the passageway in the piston rod and when the reduced portion of the pin passes this point in the down travel of the piston, any dirt or lint that has been scraped off the pin will be carried into the reduced portion of the pin and when the piston descends this reduced portion of the pin will register with the radial passageway —97— and the oil flow around the pin and through the passageway —97— will carry the dirt back into the space above the piston assembly in cylinder tube —77— and then through a slot or oil passageway 106 in the side of cylinder tube —77— above the piston travel 100 allowing the oil which has passed through the leak pin to return to the reservoir.

Altho the invention so far specifically described relates particularly to a combined pump and reservoir, yet in all cases this disclosed apparatus is considered to have a peculiar coaction in connection with a feed line or outlet tube which supplies lubricant to a plurality of metering devices communicating with the tube at points spaced different distances along the tube 110 from the pump outlet. In all cases, therefore, the applicant contemplates the connection of a tube —11— to the outlet fitting of the pump and as shown in Figure 4, tube 11 supplies lubricant to a plurality of metering devices, two of 115 which are indicated as illustrative of the fact that a large number of such devices may be fed from a single tube, and altho the particular construction of the metering unit is not an essential portion of this invention, the unit 120 illustrated comprises a T-fitting —150— inserted in the outlet line or tube —11— into which the upper end of a cylinder body member —151— is threaded.

This cylindrical member may as shown be 125 shouldered at an intermediate point to limit the downward movement of a piston —152— fitting loosely in the cylindrical body —151— so as to permit lubricant to by-pass it, spring —153— 130 acting to return the piston after each lubricant-ejecting movement as actuated by pressure in the supply line —11—.

The lower end of the body —151— is chambered and the outlet from the cylindrical portion of the body is normally closed by ball valve 135 154 under pressure of spring 155 secured in any suitable way in the chamber. Screen 156 may be provided at the upper end of the body. As stated, this particular construction is not essential to the invention, but is shown as illustrative of a satisfactory metering unit for installation in the supply line —11—.

Although I have shown and described specific structures as constituting embodiments of the 145 invention, I do not desire to restrict myself to the details of form, construction or arrangement of the same, as various changes and modifications may be made within the scope of the appended claims.

I claim:

1. A lubricating apparatus comprising a reservoir, a pump cylinder, a piston movable in said cylinder, a piston rod for actuating the piston, said piston rod formed with an axial passageway and a radial passageway leading therefrom to the interior of the cylinder, a relief pin positioned in the axial passageway and of slightly less diameter than the interior diameter of the passageway, and having a portion of decreased cross-sectional area adapted to lie opposite the radial passageway. 80
2. A lubricating apparatus comprising a reservoir, a pump cylinder, a piston movable in said cylinder, a piston rod for actuating the piston, said piston rod formed with an axial passageway and a radial passageway leading therefrom to the interior of the cylinder, a relief pin positioned in the axial passageway and of slightly less diameter than the interior diameter of the passageway and having a portion of decreased cross-sectional area adapted to lie opposite the radial passageway, and means for limiting the axial movement of the relief pin. 85
3. In a lubricating apparatus, a cylinder, a piston movable therein, a piston rod for actuating the piston, a tubular outlet fitting through which lubricant is forced from the cylinder, said piston rod having an axial passageway and a plurality of radial passageways leading from the axial passageway to the interior of the cylinder and forming a constant means of communication between the cylinder and the outlet fitting, a relief pin in said axial passageway of slightly less diameter than the interior diameter of the passageway, and means in the outlet fitting for limiting the movement of the relief pin. 90
4. In a lubricating apparatus, a cylinder, a piston movable therein, a piston rod for actuating the piston, a tubular outlet fitting through which lubricant is forced from the cylinder, said piston rod having an axial passageway and radial passageways leading from the axial passageway to the interior of the cylinder and forming a constant means of communication between the cylinder and the outlet fitting, a relief pin in said axial passageway of slightly less diameter than the interior diameter of the passageway, and means in the outlet fitting for limiting the movement of the relief pin. 95
5. A lubricating apparatus comprising a reservoir, a pump cylinder arranged therein, an outlet fitting leading from the pump cylinder, a piston movable in the cylinder, and means for maintaining constant limited communication between the reservoir and the interior of the outlet fitting. 100
6. In an apparatus of the class described, a combined reservoir and pump including a pump cylinder, a piston movable in the cylinder, means permitting limited axial movement of said cylinder as actuated by movement of the piston, and means permitting a limited amount of fluid to pass through the piston to relieve the pressure in the system beyond the piston. 105
7. In an apparatus of the class described, a reservoir, an outlet fitting leading from the reservoir and including a valve seat, an axially movable cylinder within the reservoir and having a portion adapted to contact with said valve seat, a piston movable within the cylinder and adapted to shift said cylinder axially to and from said valve seat, and means permitting a limited amount of fluid to pass through the pis- 110
- ton to relieve the pressure in the system beyond the piston. 115
8. In an apparatus of the class described, a combined reservoir and pump including a pump cylinder having an annular flange at its lower end constituting a valve face, an outlet fitting leading from the reservoir and having a valve seat of comparatively soft material for cooperation with said valve face, means permitting limited axial movement of said cylinder, a piston movable in the cylinder, spring means for actuating the piston in one direction, and a normally closed valve in said outlet fitting. 120
9. In an apparatus of the class described, a combined reservoir and pump including a pump cylinder having an annular flange at its lower end constituting a valve face, an outlet fitting leading from the reservoir and having a valve seat of comparatively soft material for cooperation with the said valve face, means permitting limited axial movement of said cylinder, a piston movable in the cylinder, spring means for actuating the piston in one direction, and adjustable means for limiting the length of stroke of the piston. 125
10. A lubricating apparatus comprising a reservoir, a pump cylinder, a piston movable in said cylinder, a piston rod for actuating the piston, said piston rod formed with an axial passageway and a radial passageway leading therefrom to the interior of the cylinder, and a relief pin positioned in the axial passageway and of slightly less diameter than the interior diameter of the passageway. 130
11. A lubricating apparatus comprising a reservoir, a pump cylinder, a piston movable in said cylinder, a piston rod for actuating the piston, said piston rod formed with an axial passageway and a radial passageway leading therefrom to the interior of the cylinder, a relief pin positioned in the axial passageway and of slightly less diameter than the interior diameter of the passageway, and means for limiting the axial movement of the relief pin. 135
12. A lubricating apparatus comprising a reservoir, a cylinder within the reservoir, a piston movable in the cylinder, means for applying pressure to the piston to move the latter along the cylinder, a second cylinder having limited movement axially with respect to the first-named cylinder, a second piston movable in a second cylinder, and a piston rod connecting said pistons. 140
13. A lubricating apparatus comprising a reservoir, a cylinder within the reservoir, a piston movable in the cylinder, means for applying pressure to the piston to move the latter along the cylinder, a second cylinder having limited movement axially with respect to the first-named cylinder, a second piston movable in a second cylinder, a piston rod connecting said pistons, an outlet fitting having a seat for the end of the second cylinder, and said second cylinder moved axially into and out of contact with said seat by frictional stress exercised by the movement of the second piston. 145
14. A lubricating apparatus comprising a reservoir, a cylinder within the reservoir, a piston movable in the cylinder, means for applying pressure to the piston to move the latter along the cylinder, a second cylinder having limited movement axially with respect to the first-named cylinder, a second piston movable in a second cylinder, a piston rod connecting said pistons, an axial passageway in said piston rod, 150

a radial passageway leading therefrom to the exterior of the piston rod and a leak pin positioned in the axial passageway and being of slightly less diameter than the passageway.

- 5 15. A lubricating apparatus comprising a reservoir, a cylinder within the reservoir, a piston movable in the cylinder, means for applying pressure to the piston to move the latter along the cylinder, a second cylinder having limited
10 movement axially with respect to the first-named cylinder, a second piston movable in a second cylinder, a piston rod connecting said pistons, an outlet fitting having a seat for the end of the second cylinder, and said second cylinder moved axially into and out of contact
15 with said seat by frictional stress exercised by the movement of the second piston, an axial passageway in said piston rod, a radial passageway leading therefrom to the exterior of the piston rod, and a leak pin positioned in the axial passageway and being of slightly less diameter
20 than the passageway.

16. A lubricating apparatus comprising a combined reservoir and pump including a pump cylinder arranged within the reservoir and having an inturned annular flange at its lower end constituting a valve face, an outlet fitting connected to the reservoir and including a passageway leading from the reservoir, said fitting having a circular flange upstanding within the reservoir and surrounding the lower end of said pump cylinder to guide the same and said upstanding flange having an opening therethrough leading from the reservoir to the space within the flange and said outlet fitting having a valve seat within the said upstanding flange and including a comparatively soft material for cooperation with said valve face, a piston movable in said cylinder, spring means for actuating the piston in one direction, and means permitting limited axial movement of said pump cylinder simultaneously with piston movement.
